UNITED STATES PATENT OFFICE.

GEORGE O. DRAPER, OF HOPEDALE, MASSACHUSETTS, ASSIGNOR TO THE DRAPER COMPANY, OF SAME PLACE AND PORTLAND, MAINE.

WARP-STOP-MOTION APPARATUS.

SPECIFICATION forming part of Letters Patent No. 618,378, dated January 24, 1899.

Application filed October 14, 1898. Serial No. 693,478. (No model.)

To all whom it may concern:

Be it known that I, GEORGE O. DRAPER, of Hopedale, county of Worcester, State of Massachusetts, have invented an Improvement in 5 Warp-Stop-Motion Apparatus, of which the following description, in connection with the accompanying drawings, is a specification, like letters and numerals on the drawings representing like parts.

10 This invention has for its object the production of a novel warp-stop-motion apparatus of that type wherein the engagement and arrest of a normally-vibrating feeler is effected by the movement into abnormal position of one of a series of vertically-movable detectors maintained by normal warp-threads in inoperative position, stoppage of the apparatus with which the stop-motion mechanism coöperates being automatically effected by or 15 20

through the arrest of the feeler.

I have herein provided a novel form of director to coöperate with a released detector due to slackness or failure of its warp-thread and insure its proper positioning to engage 25 and arrest the movement of the feeler, the director during such engagement preventing twisting or bending of the detector and at the same time providing a back-stop to act upon the upright edge of the detector opposite the edge engaged by the feeler.

30 My invention while herein illustrated as applied to a loom is not restricted to such use, as it may be applied to any form of apparatus for treating warp-threads wherein it is 35 desirable to effect stoppage of the apparatus automatically upon slackness or failure of one of the warp-threads.

Figure 1 is a longitudinal sectional view of a sufficient portion of a loom to be understood with one embodiment of my invention 40 applied thereto, taken on the line $x-x$, Fig. 2. Fig. 2 is a partial rear elevation of the apparatus shown in Fig. 1. Fig. 3 is an enlarged detail of the novel part of the mechanism 45 illustrated in Fig. 1. Fig. 4 is an enlarged perspective detail of a part of the director to be described.

The harnesses H, whip bar or roll W, lease-rods L L', and the shipper-lever S may be and

are of usual or well-known construction, and 50 in my present invention the detectors d are located back of the lease-rods, and preferably are constructed as thin metal plates provided each with a warp eye or opening d^x and with a longitudinal slot d' , herein shown as located 55 below the warp-receiving eye, the said slots of the detectors receiving a transverse bar m, extended across the loom and mounted in suitable brackets M, attached to the loom side. This bar m serves as a stop to limit the 60 descent of a released detector and also to guide said detectors when maintained in inoperative or elevated position by normal warp-threads as shown in full lines, Figs. 1 and 3.

A rock-shaft a is mounted in suitable bearings on the lower part of the brackets M, said rock-shaft having arms a', to which a feeler a^x is attached, the feeler being shown as an angle-bar with its continuous longitudinal 70 edge 6 turned toward the detectors, the feeler normally vibrating back and forth below the lower ends of the detectors, the vibration being effected in any suitable manner.

Opposite to the path of movement of the 75 feeler I have mounted the director, herein shown as a plate g, mounted on the inclined seats m^x of the brackets M and bent to form a shoulder g', extended longitudinally along the rear upright edges of the series of detectors, the plate being again bent below the shoulder to form an inclined shelf-like portion g^2 , having its edge deeply serrated or notched (see Fig. 4) to form a series of bevel-sided teeth g^3 . The toothed part of the shelf g^2 extends below the vertical path of movement of the detectors, so that when one of the latter is released by failure or slackness of its warp-thread it will descend into dotted-line position (best shown in Fig. 3) between two of the 80 teeth of the shelf, and in such position it will engage and arrest the feeler as the latter moves rearwardly or toward the detectors. At the time of engagement the shoulder g', acting in conjunction with the bottom of the 85 space between the two adjacent teeth, forms a back rest for that upright edge of the detector opposite the edge engaging the feeler.

The teeth between which the released detector stands serve to prevent twisting or bending of the detectors when engaged by the feeler, and the shelf g^2 is inclined, as shown, 5 to aid in directing the lower end of a released detector toward the toothed edge of the shelf to enter between two of the teeth thereof.

Under normal conditions it will be seen that the lower ends of the detectors project 10 below the shoulder g' , and I prefer this mode of construction, as the shoulder will thus serve at all times as a guide for the detectors.

By notching or forming teeth along the edge of the shelf g^2 of the director, as herein shown 15 and described, I am enabled to dispense with any milling, roughening, or serration of the edge of the feeler, the object of such roughening or serration in other constructions heretofore devised having been for the purpose 20 of preventing lateral twisting or slipping of the detector out of position when engaging the feeler.

The feeler is moved toward the detectors in such manner that arrest of the feeler is 25 permitted without strain or any tendency of the parts to breakage, the reverse swing of the feeler being effected positively, and for this purpose the mechanism herein shown is very convenient and will be briefly described, al- 30 though it is to be understood that any other suitable vibrating mechanism may be em- ployed.

The rock-shaft a is provided with an arm a^2 , extending oppositely to the feeler and having pivotally connected to it a bent arm a^3 , provided with a bunter a^5 and a toe a^4 , the latter coöperating with the cam D on the shaft C , which is herein shown as the cam-shaft of the loom, the bunter a^5 being thereby moved 40 into and out of the path of one or more tappets f of a cam F , also fast on the shaft C . Upon arrest of the feeler the bunter a^5 will be held up in the path of a tappet, engagement therewith acting to swing the arm a^3 to the 45 rear. The arm a^3 is slotted at a^6 to receive a stud d^6 on a short lever d^{10} , pivoted at its upper end to a link d^8 , hooked around the cam-shaft at d^9 , while the other end of the link is jointed to the arm e of a rock-shaft e^x . This 50 rock-shaft is provided with a knock-off arm e' for the shipper-lever, the lower end of the lever d^{10} and the arm e being connected by a rod e^2 , the joint e^3 of which acts as the fulcrum for the lever d^{10} when the bunter a^5 is 55 acted upon by the tappet-cam F , the swing of the upper end of said lever at such time moving the link d^8 longitudinally to operate the knock-off arm and release the shipper-handle S .

60 Various changes in the construction and arrangement of the embodiment of my invention herein shown and described may be made without departing from the spirit and scope of my invention.

65 Having fully described my invention, what

I claim as new, and desire to secure by Letters Patent, is—

1. In a warp-stop-motion apparatus, a normally-vibrating feeler, stopping means operated by or through arrest of the feeler, a director located opposite the feeler, presenting an inclined toothed guide portion, and a series of detectors vertically movable between the director and feeler and maintained inoperative by normal warp-threads, a released detector being held by the toothed guide in position to engage and arrest the feeler. 70

2. In warp-stop-motion apparatus, a normally-vibrating feeler, stopping means operated by or through arrest of the feeler, a 80 plate located opposite the feeler and bent transversely to present a lower, inclined shelf having a toothed edge, and a superposed shoulder substantially above the roots of the teeth, and a series of detectors maintained 85 by normal warp-threads in inoperative position, a released detector being directed by the shoulder and inclined shelf into position between two teeth to be thereby supported when engaging and arresting the feeler. 90

3. In warp-stop-motion apparatus, a normally-vibrating feeler, stopping means operated by or through arrest of the feeler, a director located opposite the feeler, presenting an inclined toothed guide portion and 95 a superposed shoulder inset from said portion, a series of detectors vertically movable between the director and feeler and maintained inoperative by normal warp-threads, the teeth of the guide and the shoulder holding a released detector in position to engage and arrest the feeler without being bent or twisted, and a stop to limit the descent of such detector. 100

4. In warp-stop-motion mechanism, a normally-vibrating feeler, stopping means operated by or through arrest of the feeler, a series of detectors maintained elevated and inoperative by normal warp-threads and adapted to descend into the path of and to arrest 110 the feeler when released by slackness or failure of the warp-threads, and a guide-plate opposite and downwardly inclined relative to the path of the feeler and having a toothed edge, the inclination of the guide serving to 115 direct a released detector toward the feeler and between two of the teeth of the guide, to position the detector and prevent twisting when it engages and arrests the feeler. 120

5. In warp-stop-motion mechanism, a normally-vibrating feeler, stopping means operated by or through arrest of the feeler, an inclined director located opposite the feeler and bent longitudinally to form a shoulder, the lower edge of the plate extending beyond 125 the latter and provided with teeth or notches, a series of longitudinally-slotted detectors vertically movable between the feeler and director and guided by the shoulder of the latter, normal warp-threads maintaining the de- 130

tectors out of the path of the feeler, a released detector moving into position between two of the teeth of the detector and being held thereby in position to engage and arrest
5 the feeler, and a stop-bar extended through the slots of the detectors, to limit their movement when released.

In testimony whereof I have signed my name to this specification in the presence of two subscribing witnesses.

GEORGE O. DRAPER.
